SPRAY HEAD

Oliver Isenberg, 1001 S. California Ave.,
Chicago, Ill. 60612

Filed Nov. 1, 1965, Ser. No. 87,975

Term of patent 14 years

(Cl. D91—3)

Fig. 1

Fig. 2

Fig. 3

Fig. 4

Fig. 5

FIGURE 1 is a front face view of the spray head embodying my new design;

FIG. 2 is a side view thereof, the profiles being shown in the broken out portion;

FIG. 3 is a top view with profiles shown in the broken out portions;

FIG. 4 is a top view showing the entry port to the spray head; and

FIG. 5 is a rear view.

I claim:

The ornamental design for a spray head, substantially as shown.
